DROP CORD

Filed Jan. 11, 1929

FIG. 1.

FIG. 2.

INVENTOR:
Carl D. Wayne
BY David E. Carlsen
ATTORNEY.

UNITED STATES PATENT OFFICE

CARL D. WAYNE, OF ST. PAUL, MINNESOTA

DROP CORD

Application filed January 11, 1929. Serial No. 331,812.

My invention relates to an improved flexible, electric cable of the kind commonly known or referred to as drop cords.

The main object of the invention is to provide a durable, flexible cord particularly useful for such purposes as connecting electric irons with an electric socket, for electrical-
ly operated carpet cleaners, portable motors or for any other purpose where a durable and flexible electric cord or cable is needed. Hitherto plain pairs of insulated wires wound spirally to form a cable have been commonly used and various kinds of reenforcing means used at the socket end or at the end connected to the electric apparatus, to strengthen and prolong the life of such conductor means. It is another object of my invention to eliminate the use of such reenforcing means and embody certain features of construction in the cable itself, as hereinafter fully described and as illustrated in the accompanying drawing, in which,—

Fig. 1 is a partly sectional longitudinal elevation of my improved electric cable dis-
closing a preferred construction of it.

Fig. 2 is an enlarged right hand end elevation of Fig. 1.

Referring to the drawing by reference letters, my improved cable comprises first a central cord A preferably of linen or other suitable braided, woven, or twisted fabric and having considerable strength and ample flexibility. Said cord A is imbedded in or surrounded by a non-conductive insulation B. C and D are a pair of insulated current conductors and one of which as C is designated red to differentiate between the two for reasons well known in the art.

The wires C and D are wound in close coils about the center insulation B and form the main body of my improved cable.

E is an outer coating of insulation material surrounding the coils of C and D, said coating preferably being plain rubber or sheet rubber material with imbedded woven fabric. In some cases the cable may be made with this latter coating E comprising the exterior of it but for a more expensive, slightly, and longer lasting cable a fabric covering F may be embodied although it will be readily seen

that the latter would perhaps reduce the flexibility of the cable.

In appearance the cable is plain and its conductor elements B and C are accessible at either end of the cable for connection with the terminals of any electric connection or apparatus.

The central insulation B is of course also preferably of rubber or an equivalent flexible and elastic material.

The non-elastic but flexible strand or cord A adds strength to the cable without affecting its flexibility and the elastic elements B and E give the cable the desired flexibility, the coiled conductors retained between them also having a certain amount of give or resiliency but resisting any tendency to bend or twist the cable at any point.

The central cord A is a particular feature of this device giving strength and flexibility but preventing breakage when any strain is exerted on the cable lengthwise, yet not affecting the pliability or normal bending or curvature of the cord while in use.

I claim:

A flexible cable comprising a helically ar-
ranged conducting element, a central flexible
core and a fabric cord element within said
core, and an outer coating of elastic non-con-
ductive material about said conductor ele-
ment.

In testimony whereof I affix my signature.

CARL D. WAYNE.
